CLAIM

The ornamental design for a device for non-contact measuring of deflection of roads or rails as shown and described.

DESCRIPTION

FIG. 1 is a top perspective view of a device for non-contact measuring of deflection of roads or rails according to the present invention;

FIG. 2 is a side view of the device of FIG. 1;

FIG. 3 is an end view of the device of FIG. 1; and,
FIG. 4 is a top view of the device of FIG. 1.

The broken lines in the drawings are for illustrative purposes and form no part of the claimed design. In addition, opposite side or end views can be provided as mirror images of the indicated side or end view.
